UNITED STATES PATENT OFFICE

HAROLD H. PELZER, OF ASTORIA, NEW YORK, ASSIGNOR TO SANITARY AUTOMATIC CANDY CORPORATION, A CORPORATION OF NEW YORK

DESIGN FOR A VENDING CABINET

Application filed June 5, 1930. Serial No. 35,919. Term of patent 7 years.

To all whom it may concern:

Be it known that I, HAROLD H. PELZER, a citizen of the United States of America, residing in Astoria, county of Queens, city and State of New York, have invented a new, original, and ornamental Design for a Vending Cabinet, of which the following is a specification, reference being had to the accompanying drawing, forming a part thereof.

This figure is a perspective view of a vending cabinet illustrating my new design.

The appearance of both sides of the cabinet is identical.

The rear of the cabinet is flat and unornamented.

I claim:

The ornamental design for a vending cabinet, substantially as shown and described.

This specification signed this 31st day of May, 1930.

HAROLD H. PELZER.
